WEARING APPAREL

George F. Lang, Jenkintown, Pa.

Application February 4, 1941, Serial No. 377,288

1 Claim. (Cl. 2—240)

The present invention relates to certain new and useful wearing apparel and it relates more particularly to certain new and useful combination garments including a knitted leg-encasing stocking, adapted for use with a body-encircling support and longitudinally elastic connectors detachably interconnecting said stocking and support.

One of the objects of the present invention is a more comfortable and more serviceable and durable hosiery and hosiery support whereby hosiery, particularly full-length stockings, may be more effectively supported and retained on the leg with minimum strain on the knitted fabric of the body of the stocking and with maximum protection to the knitted fabric of the body of the stocking against damaging strains, tears and runs. Another object of the present invention is to provide a stocking for use with a suitable support and providing the greatest physical comfort to the wearer as well as presenting a neat appearance.

Other objects and purposes of the present invention are apparent in the following detailed description and appended claim and in the accompanying drawings.

For the purpose of illustrating the invention, there are shown in the accompanying drawings forms thereof which are at present preferred although it is to be understood that the various instrumentalities of which the invention consists, can be variously arranged and organized and that the invention is not limited to the precise arrangements and organizations of the instrumentalities as herein shown and described.

Referring to the drawings in which like reference characters indicate like parts throughout:

Figure 1 represents a perspective view of one phase or embodiment of the present invention as it appears in actual use.

Figure 2 represents a fragmentary perspective view on a somewhat enlarged scale of the upper part of the stocking shown in Figure 1.

Figure 3 represents a fragmentary view, in elevation, of the detail of the construction, shown generally at 3 in Figure 2, but on a further enlarged scale.

Figure 4 represents a vertical cross-sectional view along the line 4—4 of Figure 3, showing the snap-fastener female member or socket-member carried by the stocking and showing a snap-fastener male member or knob-member carried by the connector; the two members being shown detached from each other.

Figure 5 represents a vertical cross-sectional 55 view similar to that shown in Figure 4, but in which the two parts making up the snap-fastener female member or socket-member are disassembled, and with the elastic band intermediate the two.

Figure 6 represents a perspective view, on an enlarged scale, of the two parts making up the snap-fastener female member shown in Figure 5.

Figure 7 represents a fragmentary, more or less schematic elevational view of the stitch formation indicated generally at 7 in Figure 2.

Figure 8 represents an enlarged elevational view of the adjoining portions of the support, connectors, and stocking shown generally at 8 in Figure 1.

Figure 9 represents a view similar to that of Figure 8 but showing the several parts as they appear when disassembled.

Figure 10 represents a more or less diagrammatic cross-sectional view, on an enlarged scale, taken generally on the line 10—10 of Figure 1 or on the line 10—10 of Figure 8.

Figure 11 represents a fragmentary perspective view of the embodiment shown in Figure 1 but shown disassociated from the body of the wearer and merely in an assembled condition.

Figure 12 represents a more or less diagrammatic or schematic top plan view of the wearing apparel shown in Figure 11, taken generally on the line 12—12 of Figure 11.

In one phase of the present invention I may provide a full-fashioned sheer hose 19 having a foot portion 20, a leg portion 21 and an upper stocking portion 22 which may be a more or less distinct welt or merely an upper leg portion of slightly heavier yarn (silk, rayon, nylon or the like) than the yarn of which the rest of the body is knitted.

An uppermost, annular band 23 of relatively 40 elastic and relatively more durable material is more or less integrally connected with said welt-like upper portion 22. As shown in Figure 3, I prefer to construct said annular band so that it has the longitudinal or circumferential elasticity but does not have transverse or vertical elasticity. The longitudinal or circumferential elasticity may be provided by constructing the band 23, with a plurality of parallel, longitudinally disposed strands 17, which are relatively more elastic than the fabric making up the remainder of the band 23. Said strands 17 may be of rubber or latex or other similar elastic material. The strands of rubber or rubber-like material 17 may be covered with a spiral wrapping of cotton, silk, rayon, nylon or the like before being incor-

55

porated into the band 23. The elastic strands are held together transversely by cotton, silk, nylon, rayon or like textile threads intertwined or interlaced therewith by weaving, braiding or knitting. The spacing between the rubber strands is such as to permit the prongs 37 of the metallic fastener or anchorage ring 36, to be hereinafter described, to pass between the rubber strands 17 without cutting or piercing them. The construction shown in Figure 3 permits a circumferential stretching without any diminution in the transverse width of the band 23 as would result if a braided material were used.

I prefer to connect said annular band 23 to said portion 22 by stitching indicated particularly in Figure 7; the portion 22 being placed so that its uppermost edge extends within the lowermost edge of the band 23. Stitching passing through juxtaposed points of said portion 22 and said band 23 may be formed by a three-needle-machine through which the stocking is passed with the outer face of the band 23 uppermost. The three needles form three annular courses of chain stitches passing through said band 23 in said portion 22 and forming parallel annular courses of loops 13, 14, and 15 upon the inner surface of the portion 22 and forming parallel annular portions 13-a, 14-a, and 15-a upon the outer surface of the band 23. Another thread 16 is shuttled back and forth through the loops 13, 14 and 15 beneath the portion 22 to provide chain stitching passing over and through each of said loops 13, 14, and 15 and serving to anchor said loops against being pulled out, as shown in Figure 7.

I prefer to construct the lower portion of said band 23 so that it contains three longitudinally disposed elastic strands 24, 25 and 26. The lowermost strand 26 is preferably placed at the lowermost edge of the band 23; the strand 24 being uppermost and the strand 25 being intermediate strands 24 and 26. As shown in Figure 7, the row of stitches forming the loops 13 is placed just below the strand 24, the row of stitches forming the loops 14 is placed along the strand 25 and the row of stitches forming the loop 15 is placed just above the strand 26.

I have found that by attaching said band 23 to said portion 22, in the manner above-described, it is possible to provide a simple and inexpensive connection between said band 23 and said portion 22 as well as one which is durable and which will transmit a minimum of "supporter strain" to the relatively less durable leg portion 21.

The elastic band 23 carries, permanently united therewith, one or more circumferentially distributed snap-fastener female members or socket members 26; these members 26 being held to the band 23 without any hole cut through said band 23 and without any sewing to the band as would tend to weaken and lessen the life of said band 23.

Said snap-fastener female member 26 includes a female engaging unit or detachable coupling unit 29 and a more or less permanent fabric-anchorage unit or backing or affixing unit 35.

The female coupling or engaging unit 29 consists of a central resilient knob-receiving socket 30 and an annular, inwardly-enlarged, peripheral anchorage channel 31.

The backing or affixing unit 35 consists of a relatively thin, annular ring 36 having a plurality of thin, bent-out pointed prongs 37 extending from the inner periphery of said annular ring 36,

generally at a right angle to the plane of said ring 36, as shown in Figures 5 and 6.

In the affixing of the female socket member 26 to the fabric, the engaging unit 29 is placed on one side of the fabric (preferably the inside) of said band 23, and the backing or affixing unit 35 is placed on the other side of said fabric with the pointed prongs 37 extending towards the fabric. When the two units are pressed together, the prongs 37 of the backing unit 35 pass through the fabric by spreading the threads apart and passing between the threads or fibres thereof, without tearing, cutting or otherwise injuring said fabric (merely pushing the threads apart from each other) and, having passed through the fabric, are bent into position and anchored within the peripheral anchorage channel 31 of the member 29. In this way, the female socket member 26 may be affixed to the band 23 without cutting the elastic strands 17 and without cutting the transverse fabric strands.

The female or socket member 26 on the stocking can be detachably united with a corresponding male or knob member 32 on a connector 40, by causing the knob of the male member 32 to enter and to be detachably held within the knob-receiving socket 30 of the female member 26.

The knob-receiving socket 30 of said female member 26 is made slightly resilient in its periphery by having its periphery slotted in a number of more or less equidistant points as at 50, so as to permit a slight spreading of the mouth of the socket 30; the resiliency of the metal tending always to contract and restore the periphery.

The male member or knob member 32, as shown on the right-hand side of Figure 4, is of a modified form of construction in which the knob portion 33 is not provided with a prong-receiving peripheral anchorage channel, but instead, a backing plate 48 is provided with a central tubular portion 49 drawn therefrom or extending therefrom which cuts through the fabric (as for instance the fabric of the connector 40 in Figure 4) and is spread out into the interior of the knob 34 of the knob portion 33 thereby permanently to hold the knob portion 33 to the fabric.

It is also possible to provide said band 23 with male engaging members (not shown) which are provided with pronged backing units and male engaging units similar in construction to the female members 26 but having a knob in place of the socket 30. In such instance, of course, a female engaging unit 26 would be provided on the connector 40.

It is also possible to provide a pronged male engaging member on the connector 40 (to be used with the female unit 26 upon the band 23) when it is desirable to avoid cutting the fabric of the connector 40.

While the detachable coupling herein shown and described possesses certain advantages peculiar to the wearing apparel of the present invention, and is therefore preferred by me, yet other quick-detachable snap-type couplings may be used, provided the annular elastic band 23 is not cut or ruptured or otherwise weakened thereby and provided the fabric is gripped or pressed between opposite pressure plates having substantial contact area with the fabric surfaces.

I prefer to knit the upper leg portion 22 of the stocking of a slightly heavier yarn than that of the main leg portion 21, as indicated more particularly in Figures 1, 2 and 3.

Thus, if the main leg portion of the stocking

is "three-thread" or "four-thread" (that is, of three-thread or four-thread silk, rayon or nylon); I prefer to knit the portion 22 of a heavier yarn, as for instance a six- to ten-thread silk (or rayon or nylon).

I prefer to construct said portion 22 of a heavier yarn to make it more durable and to minimize the possibility of "runs" or tears or other injuries developing in the main leg portion 21. It is possible, however, to affix said band 23 directly to the main leg portion 21 without any intervening portion 22.

By reason of the fact that the fastener-carrying or coupling-carrying band 23 is relatively more firm and more form-retaining than the stocking (either the leg portion or the upper-leg portion or the welt portion) and by reason of the fact that the fastener-carrying or coupling-carrying band 23 extends continuously around the upper periphery of the stocking (instead of being interrupted or instead of being fragmentary), the pull of the connector-ends at one, two, three or four points along the band 23 is transmitted to the stocking with a more uniform distribution around the circumference of the stocking. Thus, the upward pull at any one of the fastener or coupling points of the band 23 is not only transmitted to the stocking at that point, but is transmitted over a wide area on either side of said point, because of the relatively greater firmness or form-retaining character of the band 23, and because of the fact that the band itself closely hugs the leg in a continuous annular formation and is held taut under some circumferential tension, when in use.

The body-encircling member 52, shown particularly in Figure 1, is circumferentially elastic, that is, elastic in the direction of the arrows 54, namely, in the same direction in which the bands 23 are elastic.

The upper annular body-encircling member 52, with which the stocking of the present invention is adapted to be used, is preferably formed of knitted fabric with the courses disposed generally horizontally, that is, extending circumferentially around the body (in the direction of the arrows 54) and with wales extending generally vertically (in the direction of the arrows 58), and the member 52 may be circular knitted (that is, formed on a circular knitting machine) and may be formed on a double bank of needles with a double rib knit formation so as to increase its circumferential stretchability. By inlaying a rubber or other elastic thread in the member 52 in more or less circular, space zones, with the elastic threads extending circumferentially and held in place by the knitted textile threads thereof, the member 52 can be made to hug the body more firmly and thus give better support for the lower elastic bands 23 and hence to the stocking there-beneath.

Said member 52 is preferably formed with transverse or vertical elasticity in the direction of the arrows 58 as well as circumferential elasticity to give a "two-way stretch" to increase the comfort and support given to the wearer.

The member 52 may be made seamless, that is, in the form of an uninterrupted annulus.

I prefer to provide said member 52 with a plurality of downwardly-depending closed loops 55 having longitudinal elasticity in the direction of the arrows 58 and being affixed to the lower edge of the member 52 by stitching or other suitable fastening means.

The connector 40 is preferably formed with a looped portion 41 (carrying the knob member 32) and an upper loop 42 which passes over the bar 44 of a rigid connecting member 45; the loops 41 and 42 being closed by stitching 43.

The rigid member 45, as shown in Figures 8 and 9, contains a lower portion in the form of a closed loop of which the bar 44 is the base and contains an upper arm 46 which extends from the loop at one end thereof but which is separated from the loop at the other end thereof, as at 47, to permit the insertion of said member 45 into the loop 55. The unconnected end of the arm 46 is preferably turned downwardly and inwardly as at 139.

When the rigid member 45 is inserted within the loop 55, the arm 46 passes inside the loop and comes out on the other side thereof so that the turned-down end 139 encloses the loop 55 and prevents the accidental slipping out of the member 45 from the loop 55. In this way, the connector 40 may be readily attached to or detached from the loop 55 when desired.

The connector 40 is preferably formed of ordinary fabric without any added elasticity although it is possible to construct said connector 40 with vertical elasticity.

Since the knob member 32 is fastened within the outer face of the loop 41, the back face of said loop is interposed between the backing unit 35 of said member 32 and the leg of the wearer, thus preventing undesirable contact of the metal of the fastener 32 with the leg.

While I prefer to employ the loops 55, the rigid connecting member 45 and the connectors 40 to form a connection between the supporter 52 and the stocking, other methods of forming such connection are contemplated and are within the scope of the present invention.

In the embodiment shown in the drawings, I provide four snap-fastener female members 23 about the band of each stocking and four connectors 40 depending from the body-encircling member 52; two of said connectors 40 being attached to the front and back members 28 of each stocking leaving the two side members 28 unconnected.

This showing is for purposes of illustration only: it being understood that said member 52 could be provided with eight connectors 40 (that is, four for each stocking) or that said stocking could be provided with two snap-fastener members 28 (front and back) instead of four. Other possibilities are apparent and are contemplated. Thus, it is possible to provide three symmetrically disposed members 28 about the band 23 of each stocking and to provide six complementary connectors 40 upon the member 52.

By disposing the connectors 40 symmetrically in relation to the median plane of the stocking, the rear seam 74 of the stocking is centered more uniformly on the leg of the wearer, that is, centered in the vertical median plane of the leg. I prefer to distribute the fastening members symmetrically about the band 23 so that either stocking may be worn on either leg; that is, so that there will be no "right" or "left" to the pair of stockings.

The socket members 28 are comparatively thin so that they lie more or less flush in the plane of the relatively thick material of which the band 23 is formed; extending therefrom only to a slight extent, as indicated particularly in the left-hand 75 side of Figure 4. Moreover as the fabric of the

band 23 is gripped or pressed from opposite sides between substantially wide annular pressing faces or gripping faces, the pull on the coupling member is better transmitted to the fabric with less strain on the individual threads.

The annular elastic band 23 is preferably overlapped slightly at the back end of the stocking as at 76, with the overlapping edges sewn as at 77 and 78 and with the back fastening member 28 transfixing the overlap 76.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described the invention, what is hereby claimed as new and desired to be secured by Letters Patent is:

A woman's sheer full-length stocking comprising a foot portion, a sheer knitted leg portion, an annular strain-distributing band of relatively more durable fabric disposed about the 25

upper periphery of said leg portion and permanently connected therewith by stitching including a plurality of parallel annular courses of chain stitches passing through the respective marginal zones of said band and leg portion and forming loops upon the inner face of said leg portion and a shuttle thread upon the inner face of said leg portion passing through and anchoring said loops, said annular strain-distributing band being more or less form-retaining and being circumferentially relatively elastic and transversely or vertically relatively inelastic and being adapted to stretch circumferentially without any great diminution of its transverse or vertical dimension, a plurality of snap-fastener members symmetrically disposed about and generally permanently affixed to said annular strain-distributing band, said snap-fastener members comprising an engaging unit and a backing unit having thin prongs transfixing said band by passing between the thread thereof substantially without cutting or tearing the threads, said prongs being permanently interlocked within said engaging unit.

GEORGE F. LANG.
